UNITED STATES PATENT OFFICE.

FRANK M. BAKER, OF BIRMINGHAM, CONNECTICUT.

BUTTON AND FASTENING THEREFOR.

SPECIFICATION forming part of Letters Patent No. 324,212, dated August 11, 1885.

Application filed January 2, 1885. (No model.)

To all whom it may concern:

Be it known that I, FRANK M. BAKER, of Birmingham, in the county of New Haven and State of Connecticut, have invented a new 5 Improvement in Buttons and Fastenings Therefor; and I do hereby declare the following, when taken in connection with accompanying drawings and the letters of reference marked thereon, to be a full, clear, and exact 10 description of the same, and which said drawings constitute part of this specification, and represent, in—

Figure 1, a sectional perspective view of the button; Fig. 2, a back view of the button; 15 Fig. 3, a perspective sectional view of the fastening; Fig. 4, a sectional view of the button and fastening as applied.

This invention relates to an improvement in buttons, adapted to be secured to the clothing by a metallic fastening of an eyelet-like 20 character; the object of the invention being to not only firmly secure the button but at the same time grasp the edge of the fabric around the opening through which the button is attached; and the invention consists in the construction, as hereinafter described, and more 25 particularly recited in the claim.

The face of the button may be of any of the usual forms, such as seen in Fig. 1. At the 30 center is a concentric opening, *a*. On the back of the button around this opening is a downwardly-projecting flange, *b*. The fastening is of an eyelet character, the tubular portion *d* of which (see Fig. 3) is of a diameter 35 corresponding to the opening *a* through the button. On one end of the tubular portion is a flange, *e*, forming a head for the fastening. In the flange and close to the body of the eyelet is a groove, *f*, which corresponds to the 40 flange *b* on the back of the button. The length of the body of the tubular portion is sufficient to pass through the material to which the but-

ton is to be attached and project above the opening *a* in the button.

A hole is pierced in the material *A* to which 45 the button is to be attached, as seen in Fig. 4, and the tubular portion introduced through that opening, leaving the flange upon the reverse side. The button is then set over the tube, and the upper end of the tube struck 50 down into the cavity in the button. This forces the flange *b* down upon the fabric, closing the fabric around the tube into the cavity *e* in the flange below, as seen in Fig. 4, so that while the fabric is closed between the flange 55 and the back of the button, the edge of the material is held secure by the flange in the cavity, and so as to prevent the tearing away around the hole by a strain upon the button—that is to say, the flange and the cavity *e* form 60 substantially a binding for the hole through the fabric.

It is advisable to make the flange concave upon its upper side—that is, its edge turned upward to better embrace and close upon the 65 fabric; but this is not essential to my invention.

I claim—

A button having a concentric opening, *a*, with a flange, *b*, on the back around said opening, combined with a fastening consisting of the tube *d*, corresponding in diameter to the opening *a* through the button, the tube constructed with a flange, *e*, at one end, and the said flange with a groove, *f*, corresponding to 70 the flange *b* on the back of the button, the said tube adapted to extend through the fabric and through the opening in the button and be set upon the surface of the button around the opening, substantially as described.

FRANK M. BAKER.
